BEVERAGE DISPENSING FOUNTAIN

Kermit D. Huffman, Phoenix, Ariz.

Application June 24, 1949, Serial No. 3,502

Term of patent 7 years

(Cl. D2—3)

To all whom it may concern:

Be it known that I, Kermit D. Huffman, a citizen of the United States, residing at Phoenix, State of Arizona, have invented a new, original, and ornamental Design for a Beverage Dispensing Fountain, of which the following is a specification, reference being had to the accompanying drawing, forming a part hereof.

I claim:

The ornamental design for a beverage dispensing fountain, as shown.

KERMIT D. HUFFMAN.
